UNITED STATES PATENT OFFICE

WILLIAM MEDOFF, OF NEW YORK, N. Y., ASSIGNOR TO NATIONAL CELLULOSE CORPORATION, OF NEW YORK, N. Y.,

DESIGN FOR A FOLDING PAPER BOX

Application filed June 25, 1931. Serial No. 40,321. Term of patent 14 years.

To all whom it may concern:

Be it known that I, WILLIAM MEDOFF, a citizen of the United States of America, residing at New York city, county and State of New York, have invented a new, original, and ornamental Design for a Folding Paper Box, of which the following is a specification, reference being had to the accompanying drawing, forming part thereof.

In the drawing,

Figure 1 is a perspective view of the box set up ready for use; and

Fig. 2 is a planar development view of the box of Fig. 1, showing the box of Fig. 1 unfolded.

The dotted lines merely indicate where the blank is folded to make the box.

I claim:

The ornamental design for a folding paper box, as shown and described.

WILLIAM MEDOFF.
